PACKAGE FOR POPCORN AND
LIQUID THEREFOR

William E. Brown, 19 Mill St., Shelburn, Ind.

Filed July 20, 1961, Ser. No. 65,989

Term of patent 3½ years

(Cl. D58—2)

Fig. 1.

Fig. 2.

Fig. 3.

FIG. 1 is a front elevational view of a package for popcorn and liquid therefor, embodying my new design; FIG. 2 is a side elevation thereof; and

FIG. 3 is a section therethrough taken substantially on the line 3—3 of FIG. 1 and looking in the direction of the arrows.

I claim:

The ornamental design for a package for popcorn and liquid therefor, as shown.
